Inventor:

Osto Keitel.

UNITED STATES PATENT OFFICE.

OTTO KEITEL, OF WANDSEK, GERMANY.

PRESSURE-REGULATOR FOR FERMENTING LIQUIDS.

1,147,099.

Specification of Letters Patent.

Patented July 20, 1915.

Application filed April 10, 1914. Serial No. 331,066.

To all whom it may concern:

Be it known that I, OTTO KEITEL, a subject of the King of Prussia, and resident of No. 40 Hamburgerstrasse, Wandsbek, in the 5 Empire of Germany, have invented a new Pressure-Regulator for Fermenting Liquids, of which the following is a specification.

The present invention relates to an improved pressure regulator to be used in connection with the bung of casks and other 10 vessels containing fermenting liquids.

Special objects of the invention are to simplify and cheapen the construction and to render more efficient, serviceable and durable 15 in operation devices of the kind referred to.

With these ends in view the invention consists in the novel combination, arrangement and adaptation of parts, all as more fully 20 hereinafter explained, shown in the accompanying drawings and then specifically set out in the appended claim.

In the accompanying drawings Figure 1 shows the complete pressure regulator in 25 front elevation. Fig. 2 is a sectional view of the improved valve arrangement on an enlarged scale.

The complete pressure regulator is mounted on a supporting plate *a*, which is adapted 30 to be hung up at a suitable place. It comprises a tube *d* closed at one end and fitted at the other end *b* for connection with a flexible pipe leading from the bung of a cask or other vessel containing fermenting 35 liquids, a pressure gage *e* and the valve mechanism, which are both in detachable connection with the tube *d* by means of the internally screwthreaded tubular sockets or branches *c* of the latter.

40 The valve mechanism is inclosed in a casing *f* of flat cylindrical shape provided with an externally screwthreaded tubular socket *g*, which is adapted to effect a tight connection with the rearmost branch *c* of the tube

45 *d*. This casing *f* is hermetically closed at the front by a diaphragm *i* made of elastic material, preferably india rubber. The diaphragm *i* is secured in place on an internal circumferential flange of the casing *f* by 50 means of a tightly fitting lid *h* screwed into the marginal portion of the casing *f*, as shown in Fig. 2.

In a central hole of the diaphragm *i* a tubular valve *k* is tightly secured, which is 55 internally lined at the extremity entering

the casing *f* with a soft metal packing ring *l*. The bottom of the casing *f* supports a conical valve stem *m* adapted to effect a hermetic closure when in contact with the soft metal packing ring *l* of the valve *k*. 60 The external portion of the tubular valve *k* is closed by a cap *K'* having apertures *n* in its circumferential wall. Like apertures *p* are provided in the lid *h*.

A spiral spring *q* acts centrally on the cap *h'* of the tubular valve *k*. This spring *q* surrounds a cylinder *u* closed on top by a conical head *u'*. The head *u'* is of wider diameter than the cylinder *u*, so that a shoulder *u''* is formed against which the 70 spiral spring *q* abuts with its upper extremity. The lower extremity of the spiral spring *q* abuts against the flange *v* of a plunger *v'* engaging and movable up and down in the aforesaid cylinder *u*. To prevent this sliding action of the plunger *v'* being disturbed by air inclosed in the cylinder *u*, the plunger may be of polygonal cross section or it may be provided with longitudinal grooves leaving air passages open 75 or other means suitable for this purpose may be resorted to. The plunger *v'* is centrally bored at the bottom end for the reception of a projection *k''* arranged centrally on top of the cap *h'*. This projection *k''* terminates in a conical point *k'''* which presses against the ceiling *v''* of the central bore *v''* of the plunger *v'*. A small hole in the center of the ceiling *v''* accommodates the conical point *k'''* and secures the latter against 80 dislocation. The tension of the spiral spring *q* may be adjusted by means of a hollow screw stem *t* fitting into an internally screwthreaded central bushing *h'* of the lid *h*. 85

Into this hollow screw stem *t* the cylinder *u* enters and abuts therein by means of its conical head *u'*, as shown in Fig. 2. The screw stem *t* has a milled head *r*. The grooves provided in forming the milling of the head serve for fixing the screw stem *t* in its various positions, thus guarding same against accidental turning. A spring arm *s* fixed on the lid *h* engages these grooves of the milled head by means of a pointed index. By adjusting the screw stem *t* and fixing same through the agency of the spring arm *s* the pressure necessary to open the valve *k* can be regulated very exactly in accordance with a graduated scale suitably provided. When this pressure is exceeded 90

100

105

110

the diaphragm *i* lifts the valve *k* off the stem *m* allowing the surplus gas to escape through the apertures *n* and *p*.

What I do claim as my invention, and desire to secure by Letters Patent, is:

An improved pressure regulator to be used in connection with the bung of casks and other vessels containing fermenting liquids, comprising, in combination, a cylindrical 10 casing in communication with the fermenting liquid, a diaphragm closing the cylindrical casing, a tubular valve fitted in a central hole of the diaphragm, a soft metal packing ring lining in the tubular valve, a 15 fixed conical valve stem inside the casing adapted to effect a hermetic closure when in contact with the soft metal packing ring of

the tubular valve, a cap having apertures in its circumferential wall covering the tubular valve externally, an adjustable spring 20 acting centrally on the cap of the tubular valve and determining the pressure necessary to lift the valve for the escape of the surplus gas, and means for fixing the adjusted tension of the aforesaid spring, substantially as described and shown and for the purposes set forth.

In witness whereof I have hereunto signed my name this 30th day of March 1914, in the presence of two subscribing witnesses.

OTTO KEITEL.
